CHANGE PURSE

Stanley Conheim, Cranston, R.I., assignor to Ronnie Inc.,
Providence, R.I., a corporation of Rhode Island

Application June 10, 1959, Serial No. 56,304

Term of patent 3½ years

(Cl. D87—3)

FIG. 1

FIG. 3

Fig. 1 is a perspective view of a change purse showing my new design.

Fig. 2 is a side elevation thereof.

Fig. 3 is a plan view thereof with the purse in open position.

The essential features of my design are shown in full lines, the carrying chain being shown fragmentarily in Figs. 2 and 3 for ease of illustration.

I claim:

The ornamental design for a change purse, as shown and described.
